Application November 22, 1938, Serial No. 241,774

3 Claims. (Cl. 146—49)

This invention relates to a machine for removing the skin or peel of vegetables and fruits, and more particularly pertains to a construction and arrangement of abrasive surfaces to the action of which the articles to be peeled are subjected by causing the articles to be tumbled and revolved in contact with the abrasive surfaces.

An object of the invention is to provide a machine of the above character embodying a cylindrical container fitted with a revolving bottom wall in which said bottom wall and the inner periphery of the cylindrical walls of the container are surfaced with an abrasive composition of a character which is highly effective in its abrasive action on fruits and vegetables tumbled and scraped thereagainst, and which abrasive is initially in the form of a plastic and capable of being readily applied to the walls of the container and to the revoluble bottom thereof both in initial construction of the machine and in effecting repairs thereof.

Another object is to provide a construction whereby the upper face of the bottom wall may be readily equipped with deflecting ribs so formed and arranged that during operation of the machine the contents of the container will be tumbled, deflected, and turned over, in such fashion that all portions of the surfaces thereof will be brought rapidly in and out of contact with the abrasive surfaces of the machine so as to effect rapid and thorough removal of the skins or peel of the articles being worked, and in which the deflectors are so formed and arranged as to protrude from the working abrasive surfaces in such fashion as not to subject the articles being worked to excessive impacts or effect excessive abrasive or mutilating action on such articles.

Another object is to provide a fruit and vegetable peeler embodying a housing having a side wall discharge opening fitted with a closure which is so constructed that when in its open position it will constitute a discharge chute so as to facilitate emptying the housing of its contents and directing such contents into a receptacle.

Another object is to provide a construction in the closure whereby a seal is afforded for a hinged joint thereof such as to prevent clogging of such joint when the closure is open and contents of the housing are being ejected therefrom.

Another object is to provide an abrasive composition for vegetable and fruit peeling machine which is highly durable and efficient, which is insoluble in water and practically acid proof, and which is not subject to deterioration or dis-

integration to any appreciable extent either while standing or during operation of the machine.

With the foregoing objects in view, together with such other objects and advantages as may subsequently appear, the invention is carried into effect as illustrated by way of example in the accompanying drawings, in which:

Fig. 1 is a horizontal section and plan view of the machine;

Fig. 2 is a view in vertical section taken on the line 2—2 of Fig. 1 with parts in elevation showing the closure in its closed position;

Fig. 3 is a detail in section as seen on the line 3—3 of Fig. 1;

Fig. 4 is a view in horizontal section taken on the line 4—4 of Fig. 2, with the closure in its open position;

Fig. 5 is a vertical section taken on the line 5—5 of Fig. 4 depicting the discharge opening closure in its open position and showing the manner of sealing the hinged joint thereof;

Fig. 6 is a view of the machine as seen in front elevation with the closure closed;

Fig. 7 is a detail in section taken on the line 7—7 of Fig. 6; and

Fig. 8 is an enlarged detail plan view as seen in the direction indicated by the arrow 8 in Fig. 2.

Referring to the drawings more specifically, A indicates generally the peeling machine housing which embodies a cylindrical side wall 9 and an inclined bottom wall 10, which housing is carried on a hollow base 11. The housing A is open at its upper end and is adapted to receive a loose cover B which is provided with a marginal flange 12 adapted to seat on the upper end of the cylindrical side wall 9 and which cover has a downwardly inclined central portion 13 leading to an opening 14; the cover B serving as a hopper through which articles to be peeled may be directed into the housing.

The lower portion of the bottom wall 10 connects with a discharge pipe 15 through which washing liquid is discharged.

Mounted on the base 11 is a standard 16 which projects upwardly through the bottom wall 10 and in which is revolvably mounted a vertically extending shaft 17 which seats on roller bearings 18 carried in the standard 16. The shaft 17 has its lower end portion extending through the top wall of the base 11 and fitted with a pulley 19 for engagement with a driving belt 20 whereby the shaft 17 may be driven from any suitable source of power such as a motor C carried on the base 11. The upper end portion of the shaft 17 projects above the standard 16

and is detachably engaged with the under side of a rotary table D.

The rotating table D embodies a circular pan 21 affixed to the shaft 17 and which pan carries an abrasive body 22 composed of a substance that is plastic when heated and is solid at atmospheric temperature and which material is reinforced by a wire screen 23 embedded therein. The upper surface of the abrasive body 22 is substantially flat throughout and extends on a plane with the margin of the rim of the pan 21 except as to radial portions thereof as will be presently described.

As a means for effecting tumbling of articles carried on the table D during rotation thereof the table is fitted with a pair of ribs 24 which protrude slightly above a portion of the upper surface of the abrasive 22 and which ribs are of equal width throughout their lengths and are rounded upwardly across their tops. The ribs 24 are here shown as smooth throughout the exposed surface thereof but in some instances it may be desirable to extend a coating of the abrasive material 22 thereover.

As here shown in Fig. 3, the ribs 24 are formed integral with the bottom of the pan 21 and are arranged in offset relation to each other on opposite sides of a line extending diametrically of the pan and with the exposed curved faces thereof presented toward the direction of rotation of the table D. The surface of the abrasive body 22 is sloped or inclined from the upper rear margins of the ribs 24 to the level of the flat portion of the body as indicated at 25.

The cylindrical side wall 9 of the housing A is lined throughout on its inner periphery with an abrasive material 26 of the character employed on the rotating table D and which material is reinforced by a wire netting 27 overlying the inner periphery of the wall 9.

In order to facilitate the discharge of articles from the housing A the side wall 9 thereof is formed with a discharge opening 28 fitted with a closure E comprising a pair of doors 29 and 30 curved to conform with the cylindrical contour of the housing wall 9 and carried on hinges 31 and 32 respectively to swing outwardly and horizontally relative to the housing side wall. The inner faces of the doors 29 and 30 are formed with an abrasive coating 33 corresponding to and extending in continuation with the abrasive coating 26 on the wall 9 when the closure E is closed. The closure E is arranged to extend adjacent the lower inclined portion of the bottom wall 10 and to extend below the plane of the underside of the rotary table D, and mounted on the inner lower marginal portions of the doors 29 and 30 are panels 34 and 35 formed to swing in and out of the opening 28 on swinging the doors, and which panels are disposed immediately below the underside of the table D when the doors are in their closed position, and are adapted to project from the lower marginal portion of the table D outwardly through the opening 28 when the doors are disposed in their open position as shown in Fig. 4, whereby the panels 34 and 35 and doors 29 and 30 collectively serve as a chute to direct the contents of the housing A into a suitable receptacle either on tilting the housing to discharge its contents through the opening 28 or under the action of the rotating table D or both.

The abrasive material employed in coating the table D, wall 9 and closure E preferably comprises a composition consisting of a mixture of

three parts of hard sharp abrasive in comminuted form and one part of Portland cement thoroughly intermixed, to three parts of which mixture is added one part of tar or asphalt which constitutes a binder which is impervious to water and is insoluble therein. Mixture of the ingredients is effected by heating the tar or asphalt to a melting temperature and then intermixing the abrasive and cement therewith. The resultant mixture while warm is in a plastic state and may be readily applied to the wire covered surfaces of the machine and smoothed to afford the requisite abrasive surface. The composition when cold or at atmospheric temperature is quite hard and sufficiently abrasive in character as to effect the desired abrasive action upon fruits and vegetables.

In order to insure a thorough bond between the plastic abrasive and the bottom wall of revolute pan 21, such wall is formed with a series of closely arranged perforations *a* the margins of which flare outwardly and downwardly, so that on applying the plastic abrasive to the pan under sufficient pressure portions of the plastic will be forced into the perforations to fill the latter and thereby form keys *b* when the plastic hardens that will act to securely anchor the plastic in place.

The doors 29 and 30 are mounted on a rectangular frame F which borders the opening 28 and on which the stationary leaves of the hinges 31 and 32 are formed, and carried by the side members of the frame F are stops 36 and 37 arranged to limit opening movement of the doors 29 and 30 so that the doors will extend substantially parallel with each other when in their open position as particularly shown in Fig. 4.

In the arrangement here shown the door 29 is disposed on the side of the opening 28 presented toward the direction of travel of the margin of the table D on rotation of the latter, whereby on opening the doors to a position in which they extend in substantially parallel relation to each other the contents of the housing on being ejected through the opening 28 by the action of the rotating table D will in part be directed against the inner side of the door 29.

In order to prevent the materials being ejected through the opening 28 from becoming lodged in the joint between the door 29 and the side margin of the opening 28, the inner edge of the door is formed with a flange 38 which extends inwardly so as to overlie the inner face of the side margin of the opening 28 when the door 29 is closed, as shown in Fig. 1, and to project across the margin of the opening and cover the joint between the door and margin of the opening 28 when the door is open, as shown in Fig. 4.

In order to prevent the materials being discharged from the housing from entering the gap between the overlying panels 34 and 35 carried on the doors, the panel 35 on the door 30 is arranged to overlie the panel 34 on the door 29 so that the gap between the panels will open in the general direction of travel of the table D whereby materials passing through the opening 28 in the direction of the door 29 will flow over the uppermost panel 35 and be directed in part onto the lower panel 34.

Means are provided for securely fastening the doors 29 and 30 in their closed position which means is here shown as embodying a rocker arm 39 which is pivoted intermediate its ends on a pin 40 carried by the door 29 adjacent the free end thereof, and which rocker arm is engageable

at its ends with a pair of oppositely extending lugs 41 and 42 formed on the upper and lower rails of the door frame F; the lever arm being fitted adjacent one end thereof with a handle 5 43 by which it may be readily swung in and out of engagement with the lugs 41 and 42. The free end of the door 29 is formed with a marginal flange 44 arranged to overlie the adjacent edge of the door 30 when the doors are in their closed 10 position as shown in Fig. 1.

As a means for directing wash water into the housing A during operation of the machine and to effect flushing thereof, a water inlet pipe 45 is mounted to extend into the upper portion of the 15 housing through the upper member of the frame F; the inner end of the pipe 45 constituting a nozzle which is arranged to direct water discharged therefrom against the underside of the inclined wall 13 of the cover B such that the 20 latter will act as a deflector and serve to break up and distribute the stream entering the housing.

In order to prevent clogging of the gap extending between the outer periphery of table D and the inner periphery of the housing side wall 9, as 25 might be occasioned by accumulation or wedging of particles of materials being worked in such gap, the rim of the table is fitted with a plow 46 which extends into the gap as particularly shown 30 in Fig. 8. The plow 46 is here shown as formed on the end of the rib 24 in continuation thereof and as having an inclined face which projects downwardly along the outer face of the rim of the pan 21 as shown in Fig. 2, so that on rotation 35 of the table the plow will act to dislodge pieces tending to wedge between the table and the housing.

In the operation of the invention the articles to be peeled are placed in the housing A and the 40 table D set in motion with the articles imposed thereon. As the table revolves it will move relative to the articles disposed thereon such as to effect abrasion of the peelings thereof. The straight rib 24 will advance under the mass of 45 articles supported on the table and will effect a turning action thereon so as to present changing surfaces to the abrasive action of the table.

At the same time portions of the articles will be carried outwardly under the urge of centrifugal force and thereby be caused to ride over the abrasive on the inner wall surface of the walls of the housing and the doors. The ribs 24 thus serve to maintain the articles being worked in a state of agitation under the urge of the revolving table D whereby excessive wearing away 50 of the fruit or vegetables being peeled may be avoided. During the abrasive action a spray of water is delivered to the interior of the housing through the pipe 45 whereby the parings are 55 washed from the articles and from the abrasive surfaces and delivered to discharge through the pipe 15 in the inclined bottom wall 10 of the housing.

60 On completing the abrasive action on the materials being peeled the closure E is opened while the table D is revolving so that the latter will act to eject the contents of the housing outwardly through the opening 28 and onto the trough formed by the panels 34 and 35. Discharge of the contents of the housing may thus be effected by the action of the rotary table but in some instances removal of the contents of the housing may be effected by tilting the latter with 65 the opening 28 and opened door 29—39 extended

downwardly so that the contents of the housing will pass to discharge through the opening.

By providing the housing with the side wall opening 28 the rotary table D is rendered readily accessible to permit its removal and replacement 5 which may be readily effected by reason of its screw threaded engagement with the shaft 17 which threaded connection is opposite that of the direction of rotation of the table D so as to tend to tighten the screw on driving the shaft 17 in 10 its forward direction.

An important feature of the invention resides in forming the rotating table D with the straight ribs 24 having an upwardly curved smooth portion presented to the direction of advance of the 15 ribs, that is on the leading edge thereof, together with the relatively long downwardly inclined face 25 of the abrasive leading from the trailing edge of the rib, since by this construction, the articles being peeled, on being impacted by the advancing 20 ribs will be caused to roll upwardly over the ribs and then pass onto the abrasive surface with a rolling motion and without being thrown and caused to strike the abrasive surface of the table with an excessive impact, thus minimizing formation 25 of flat surfaces on the peeled articles.

Another important feature is the formation of the abrasive inner surface of the housing side wall free of protuberance other than that afforded by the slight roughness of the abrasive, so as 30 to minimize tumbling of the articles as they are advanced along the side wall of the housing against the abrasive surface thereof.

While we have shown and described a specific embodiment of our invention we do not limit ourselves to the exact details of construction and arrangement shown but may make such changes in the parts and in their arrangement as occasion may require coming within the meaning and scope of the appended claims. 35

We claim:

1. In a vegetable peeler, a vertically extending cylindrical housing, a circular horizontal rotary abrasive table in said housing having its margins spaced from the inner periphery of said housing, 45 a rib protruding from the upper surface of said table leading outwardly from the center to the margin thereof, and a plow formed on the outer end of said rib projecting beyond the margin of 50 said table and protruding downwardly into the space between the margin of the table and the inner periphery of the housing.

2. In a vegetable peeler, a vertically extending cylindrical housing, a horizontal rotary abrasive table in said housing, a rib protruding from the 55 upper surface of said table leading outwardly from the center to the margin thereof, and a plow formed on the outer end of said rib projecting beyond the margin of said table, said rib being formed with a rounded upper surface one marginal portion of which projects abruptly from said table and the other marginal portion of which is covered by an inclined abrasive body leading to the top of said table.

3. A rotary abrasive table comprising a pan 65 formed with a rib extending radially thereof and projecting above the plane of the rim of the pan, said rib being rounded on one side thereof, and an abrasive composition in said pan above which the rounded portion of said rib projects, said composition having an inclined surface portion leading to the upper portion of said rib on the side thereof opposite the rounded portion. 70
